(57) **CLAIM**

We claim the ornamental design for a transducer holder, as shown and described.

DESCRIPTION

FIG. 1 is a first perspective view of a transducer holder, showing our new design;

FIG. 2 is a left side view thereof;

FIG. 3 is a right side view thereof;

FIG. 4 is a rear view thereof;

FIG. 5 is a front view thereof;

FIG. 6 is a top view thereof;

FIG. 7 is a bottom view thereof;

FIG. 8 is a second perspective view thereof; and,

FIG. 9 is a cross-sectional view thereof, taken along line 9-9 in FIG. 6.

1 Claim, 7 Drawing Sheets
